UNITED STATES PATENT OFFICE.

EZRA W. CARTER, OF COHOES, NEW YORK.

DESIGN FOR A DRAIN OR OTHER PIPE.

SPECIFICATION forming part of Design No. 19,731, dated April 1, 1890.

Application filed March 10, 1890. Serial No. 343,411. Term of patent 14 years.

To all whom it may concern:

Be it known that I, EZRA W. CARTER, a citizen of the United States, residing at Cohoes, in the county of Albany and State of New York, have invented and produced a new and original Design for a Drain or other Pipe, of which the following is a specification.

My design relates to drain and other pipes; and the leading feature thereof consists in a cylindrical section of a pipe or tube having upon its extremities semicircular or substantially semicircular collars or strips, partly overlapping upon the exterior surface of the pipe-section and in part extending beyond the ends of such pipe-section, said collars or strips being arranged upon alternate or opposite sides of the pipe-section.

To more fully disclose said design I will make reference to the accompanying drawing, in which the figure is a perspective view of my design.

In the said drawing, the reference-numeral 1 denotes a section of pipe of cylindrical form, or substantially so, and of any preferred length. Lapped upon each end of the tubular section is a semicircular or substantially semicircular collar or strip 2, applied directly

to the exterior surface of the pipe, one portion of said collar projecting beyond the end of the pipe-section, while the other and remaining portion is lapped upon the half-circumference of said pipe-section. These semicircular collars are formed upon opposite or alternate sides of the pipe-section in contradistinction to applying them to the same side having relation to a plane passing longitudinally through the axis of the pipe.

What I claim as my design is—

The design for a section of pipe herein shown and described, the same consisting of a tubular section provided at its end with substantially semicircular collars partly lapped on the exterior of such tubular section and partly projecting beyond the ends thereof, said collars being arranged upon opposite or alternate sides of the pipe-section, substantially as described.

In testimony whereof I have affixed my signature in presence of two witnesses.

EZRA W. CARTER.
